United States Patent Office.

S. B. DOUGHERTY, OF SOUTH BERGEN, NEW JERSEY.

Letters Patent No. 91,725, dated June 22, 1869.

IMPROVEMENT IN SAFETY-VALVE.

The Schedule referred to in these Letters Patent and making part of the same.

To all whom it may concern:

Be it known that I, S. B. DOUGHERTY, of South Bergen, in the county of Hudson, and State of New Jersey, have invented a new and useful Improvement in "Safety-Valves" for locomotive-engines and other boilers, of which the following is a full, clear, and exact description, reference being had to the accompanying drawing, forming part of this specification, and in which—

Figure 1 represents a sectional elevation of a safety-valve constructed in accordance with my invention, and

Figure 2, a plan of the valve-box or seat-portion of the valve.

Similar letters of reference indicate corresponding parts.

My improvement has reference to that description of safety-valves in which a large area of escape is provided for the steam under a small load or weight upon the valve, by giving to the valve a hollow form, so that when down on its seat or seats, it has an annular exposure to the steam, and when lifted, opens escape for the steam both through and around and outside of it. In safety-valves of this description, there has usually been great difficulty in making the valve bear with uniformity on both of its seats so as to secure a close fit of the valve when closed, by reason of the expansion and contraction which take place, under exposure to the steam, of the intermediate portion of the valve that connects the upper and lower bearing-surfaces of the valve, and which, being generally in the form of a long cylinder or tube, favors such objectionable expansion and contraction, and virtually makes of the two valve-bearing surfaces, two valves.

My invention obviates these difficulties, and includes a tapering construction of the valve, so that its two bearing-surfaces lie in the same conical figure or outline, and the seats on which the valve rests are similarly disposed, and in close relationship to each other, whereby not only are the disadvantages hereinbefore specified avoided, but increased facility is afforded for construction of the entire valve.

Referring to the accompanying drawing, the valve-box or seat is made up of inner and outer cylindrical portions A and B, both of which are open at their top, and the outer one, A, opens also below, but the inner one, B, closed at its bottom.

On the upper edge of these cylinders A and B, are

formed valve-seats *a* and *b*, both of which are disposed to lie in the same conical outline or figure, so that on a straight-edge being applied to their faces, to connect them, the same will touch or lie on both faces.

This construction, which also applies to the outer or bearing-surfaces of the valve C, largely facilitates the true turning and fitting of the valve and its seat or seats. Such arrangement of the seats *a* and *b*, in fact, makes of them but one, and the valve-bearing surfaces being in line, or extensions one of another, constitute but the one valve in the strictest sense of the term.

This valve C, which is of a hollow tapering form, is open above and below, and may be guided in its play by wings *c c*, arranged to project from a central tubular portion, *d*, and made to freely fit the inner cylinder B.

The outer cylinder A may be joined to the inner one by means of radial connections *e*.

It will be observed that the valve C, when down, secures an annular presentation of it to the steam, which is admitted from below between the two cylinders A and B, without exposing the valve to any undue or irregular expansion and contraction of metal out of line with the seats, which insures a tight fit of the valve to both of its seats, or divisions of the one seat, as they may be termed.

When the valve is raised, escape for the surplus steam is provided, both through it and outside of or around it.

Either a spring, direct weight, or lever and weight, may be applied to keep the valve closed, and if a spring, it may either be applied in a direct manner, as represented in the drawing, or to act upon the valve through the intervention of a lever.

An upper or outer case may be used, if desired, to give to the safety-valve a lock-up character.

What is here claimed, and desired to be secured by Letters Patent, is—

The hollow tapering valve C, having its outer bearing-surfaces in line, as described, in combination with the cylinders A and B, arranged as specified, and having the valve-seats *a* and *b* disposed to lie in the same conical line or figure, substantially as herein set forth.

S. B. DOUGHERTY.
